ORE PULVERIZER

Cyrus R. Brown, Denver, Colo., assignor of fifty percent to Charles N. Ford, Springer, N. Mex., and fifty percent to Sim Calley, Wagon Mound, N. Mex.

Application June 8, 1937, Serial No. 146,980

3 Claims. (Cl. 83—12)

This invention relates to improvements in ore crushers and pulverizers for use in powdering crystalline material, and preparing ores for mineral separation treatment.

5 This application relates more particularly to an improvement in the construction of the mill described and claimed in application Serial No. 77,478, filed May 2, 1936, by Rupert H. Enoch.

Gold, and sometimes other minerals, nearly 10 always occur in metallic state in quartz and other rock formations and it is customary to grind the ore to liberation in ball or rod mills where the material is subjected to attrition in such a manner that the gold freed from the quartz 15 is reduced to very small particles that are difficult to recover by ordinary methods.

It is evident that a great advantage would be gained if the metallic gold could be freed from the gangue without further subdividing it and 20 this may be effected by means of a device employing a crushing action in lieu of a grinding action.

In the ore pulverizing device described and claimed in the above identified application, the 25 mineral is released from the gangue or non-mineraliferous portions by a crushing action effected by passing the ore, which has first been reduced to about 1" minus, successively between a number of pairs of cylindrical rollers that are 30 biased towards each other by powerful springs.

In order to quickly pulverize the ore, it is passed in succession between several pairs of rollers; each successive pair reducing still further the ore delivered to it.

35 It has been found that the peripheral speed of the several pairs of rollers must be increased from the first to the last so that the capacity per unit time of each succeeding pair of rollers will remain the same or increase from the first 40 towards the last.

In the machine, of which this is an improvement, the rollers of each pair are normally in contact and the entire force of the springs that tend to move the rollers towards each other is 45 resisted by the rollers themselves and their trunnions and bearings. The result of this is that the pressure against the rollers and their bearings is almost as great when the machine is running idle as when it is working and this makes 50 it very difficult to start.

It has been found that a successful operation of a roller type of pulverizer does not require the surfaces of the rollers to come into actual contact. If, for example, the ore is to be reduced 55 to particles no greater than one one-hundredth

of an inch, this will be effected if the surfaces of the rollers are normally spaced this distance apart.

It is evident that so long as the surfaces of the rollers do not come into contact, there will 5 be no pressure transmitted through them to the bearings in which they are journalled when the machine is idle.

One of the objects of this invention is to provide an ore pulverizer composed of one or more 10 pairs of cylindrical rollers mounted for rotation in bearings, the bearings of each cylinder or roller being movable towards and away from the bearings of the other roller, and in which the bearings of at least one of the rollers is acted 15 upon by powerful springs that tend to move them towards the bearings of the other cylinder and against adjustable stops positioned between the opposed bearings for limiting the movement of the rollers towards each other, thereby keeping 20 the surfaces of the rollers out of actual contact.

Another object of this invention is to so proportion the capacities of the several pairs of rollers arranged in tandem relation and spaced progressively shorter distances apart that each pair 25 of rollers will have a slightly greater capacity than the pair directly above for the purpose of preventing clogging that would otherwise take place, due to the smaller distance between the rollers. 30

The above and other objects that may appear as the description proceeds are attained by means which will now be described in detail and for this purpose reference will be had to the accompanying drawings in which the invention has 35 been shown in its preferred embodiment and in 40 which

Figure 1 is a side elevation of the machine, portions having been broken away to better show the construction;

Figure 2 is an end elevation, looking in the 40 direction of the arrow 2, portions being broken away to better show the construction;

Figure 3 is a view looking downwardly through plane 3—3, Fig. 1; the housing being shown in 45 section on a horizontal plane;

Figure 4 is a section taken on line 4—4, Fig. 3;

Figure 5 is a section taken on line 5—5, Fig. 3; and

Figure 6 is a section taken on line 6—6, Fig. 3.

In the drawings, reference numeral 10 designates the upright corner posts of the frame of the machine. These posts are connected at their upper ends by cross members 11 that are secured in place by means of bolts 12 or other suitable means. Extending between the two upright cor- 50 55

ner posts on one side, are channel beams 13, these are spaced one above the other in the manner shown most clearly in Fig. 1. The beams are supported from the corner post by means of angle brackets 14 and are positioned with their open side towards the top. Extending between the front and rear corner posts on each side are heavy steel bars 15, which are provided at their ends with nuts 16. Positioned in the channels 5 are bearing blocks 17 and 18 and these are provided with openings for the bolts 15. Bearing block 17 is spaced from the adjacent corner post by means of a spacer 19. The bearing block 18 is slidable on the bolt 15 and is biased towards the block 17 by means of a heavy helical spring 20 that extends between the block 18 and a housing 21 that is slidable on the bolt. This housing is shown most clearly in Figs. 3, 4 and 5 and will be described more in detail as the description proceeds. Journalled between the pairs of bearing blocks 17 and 18 are cylindrical rollers 22 provided at their ends with trunnions or shafts that extend through the bearing blocks in the manner indicated in Fig. 1. The rollers are 10 formed with hardened steel surfaces and one roller of each pair is provided at its ends with plates 23 that project beyond the periphery of the roller in the manner shown in Fig. 1. Plates 23 lap the ends of the other roller of the pair 15 and serve to guide material into the space between the rollers. Extending through the right hand roller of the upper pair, as shown in Fig. 1, is a shaft 23a. A fly wheel 25 is connected to one end of this shaft and a belt pulley 26 is 20 connected to the other end thereof. Positioned 25 between the fly wheel and the frame is a sprocket wheel 27 that cooperates with a sprocket chain 28 which, in turn, is operatively associated with a sprocket wheel 29 carried by the shaft of the 25 roller directly beneath. The other end of this 30 shaft is also provided with a sprocket wheel 30 that cooperates with a sprocket chain 31, which, in turn, cooperates with a sprocket wheel 32 on the shaft of the roller directly beneath. The 35 other end of this same shaft is provided with a sprocket wheel 33 that transmits motion by means of the sprocket chain 34 to the next lower roller and this continues until the lowermost roller of the series is reached. The diameters of the several sprocket wheels are so proportioned that the driven roller of each pair increases in 40 peripheral speed downwardly, for example, the peripheral speed of the rollers of the second pair from the top is greater than the peripheral speed of the top roller and the peripheral speed of the third roller from the top is greater than that of the roller directly above. The object in this is to equalize the capacity of the several rollers to compensate for the different distances 45 apart when the pulverizer is operating.

It is well known that a solid, such as a piece of ore will take up more space after it is crushed than before; this is due to the interstitial cavities in the crushed ore and the cubical volume 50 of a given volume of a frangible solid will increase in proportion to the extent of its subdivision.

In order therefore to enable the crusher to be operated at maximum capacity and to keep the 55 surface of the rollers of each pair closer together as the crushing progresses, the peripheral speeds of each successive pair of rollers must be increased. If we disregard the increase in volume due to the crushing, then the length of the rollers times the distance between them, times the

peripheral speed should be equal for all of the successive pairs. Due to the increase in volume with the successive crushing operations the peripheral speeds should increase faster than the decrease in the distance between the rollers. The 5 top of the frame or assembly is provided with a hopper 35 which serves to direct crushed ore into the space between the uppermost pair of rollers and as these are driven in such directions that their adjacent surfaces move downwardly, the 10 material that falls into the space between the rollers after being reduced in size is fed to the pair of rollers directly beneath, and this continues until the material reaches the bottom, when it is discharged into the opening 36. The 15 roller assembly is enclosed in a housing comprising side members 37 and end members 38. The function of the housing is to keep the dust from escaping into the surrounding air, and to act as a guide to direct the material to the discharge 20 opening.

Referring now more particularly to Fig. 6, in which the channel 13 has been shown in longitudinal section, as have also been shown the bearing blocks 17 and 18, it will be seen that 25 the bearing blocks are separated by means of two spacers 39 and 40. By referring to Fig. 3, it will be seen that the spacer blocks 39 and 40 are each provided with an inclined edge 41 so that each block is in effect a wedge. Block 40 30 has a threaded opening 42 through which a bolt 43 extends. This bolt passes through the flanges of the channel and is provided on the outside with a head 44 and on the inside with a nut 45 that is held against rotation by means of a pin 35 46. It is evident that by rotating the bolt 43, the block 40 will be moved transversely of the channel and will thereby alter the distance between the adjacent surfaces of the bearing blocks 17 and 18.

From Figs. 3, 4 and 5 it will be seen that the bolts or rods 15 are provided near one end with a threaded section 47 on which is rotatably mounted a nut 48. This nut is formed by a worm gear whose toothed periphery has been 45 designated by reference numeral 49. Collars or bushings 50 serve to space the nut 48 equidistantly from the opposite walls of the housing 21. One end of the spring 20 abuts the outside 50 wall of the housing in the manner quite apparent from an inspection of Figs. 1, 3 and 4. Since there are two channel bars 13 for each set of rollers, there are also two sets of bolts or bars 15 for each set of rollers, as indicated more 55 clearly in Fig. 2. In order to adjust the tension of the springs of each bar uniformly and simultaneously, the nuts 48 are interconnected by means of a shaft 51 that carries a worm 52 which cooperates with the worm gear 49 in a manner 60 shown most clearly in Figs. 4 and 5. Sleeves 53 serve to hold the worm 52 in a central position and are themselves held in adjusted position by means of pins 54. Shaft 51 is provided at one end with a hand wheel 55 by means of 65 which the shaft and the two worms 52 can be simultaneously rotated, thereby effecting a simultaneous and equal adjustment of the tension of springs 20.

It has heretofore been explained that the principal object of this invention is to provide a machine of the type illustrated with means for holding the rollers of each pair in predetermined spaced relation in opposition to the action of the springs, and this is effected by means of the 75

wedges 39 and 40 whose relative positions can be adjusted by means of the bolts 43.

The material that is fed into the hopper is first crushed to a 1" minus size and the rollers of the upper pair are spaced a considerable distance apart, but are close enough to effect a considerable reduction of the ore as it passes between them. The ore from the upper pair of rollers drops into the space between the rotating rollers of the pair directly beneath, which are adjusted closer than the pair directly above and rotated at a greater peripheral speed, and is there further reduced. From this pair of rollers the ore passes through the pair directly beneath and this is continued until it has passed between all the different series of rollers and is reduced to the size desired. The lowermost pair of rollers is adjusted so that the surfaces are very close together but are still out of contact, and therefore, when the machine is running idle, the pressure exerted by the springs 20 is not transmitted to the rollers and their bearings but is opposed entirely by the spacer blocks 39 and 40, and therefore the power required to start the crusher 25 and to run it when idle, is very much less than would be the case if the pressure exerted by the springs were transmitted to the roller surfaces and to their bearings. It is evident that the crushing and pulverizing can be effected just as 30 well and perhaps better by rollers that are spaced apart a short distance than if the peripheral surfaces were in actual contact.

It is evident that when ore is fed to the space between any pair of rollers, it will tend to move the rollers apart and this can only be effected by overcoming the force exerted by the springs and also the inertia of the parts. The pressure of the springs is adjusted so as to get the effect desired and no greater force should be employed 40 than is necessary to obtain the desired results.

The housing 21 is slidable in the channels 13 in the manner quite apparent from Figs. 3, 4 and 5. Since the bolts or bars 15 extend entirely through the frame and are provided at their 45 ends with nuts 16, they resist the force tending to separate the rollers and there is therefore no strain put on the connections between the channels 13 and the corner posts.

Attention is called to Fig. 1 in which the space 50 between the uppermost pair of rollers has been designated by letter s and to the space between the rollers directly beneath where the corresponding space has been designated as s'. The spaces between the rollers of each pair decreases downwardly, but the rollers do not come into actual contact.

By the expedient of increasing the peripheral speeds of the rollers of each succeeding pair, it is possible to effect a desired reduction with exactness because the material does not crowd and separate the rollers. If the successive pairs of rollers were of the same length and rotated at the same peripheral speed, the distance between the surfaces of successive pairs would have to 60 increase slightly in order to prevent clogging.

In the embodiment herein described and shown on the drawings, means has been provided for simultaneously and equally adjusting the two bearings for each roller and this is believed to 65 be novel in machines of this class.

For the purpose of assisting in directing the materials into the space between the rollers deflector plates 68 may be provided whenever desired.

70 Since this invention is an improvement only,

on the machine shown and described in the application above identified, it is not the intention to claim in this application anything that is disclosed in the said application, except as the elements form a new combination. 5

Having described the invention what is claimed as new is:

1. An ore crusher and pulverizer comprising in combination, a supporting frame having vertical end members connected by a plurality of 10 pairs of side members of channel cross section with the flanges pointing upwardly, the channels of each pair being on the same vertical level, a stationary bearing and a movable bearing supported on each side member, a roller mounted 15 for rotation between each pair of stationary bearings, another roller mounted for rotation between each pair of movable bearings and means for interconnecting the several rollers journaled in the stationary bearings to obtain simultaneous rotation, the interconnecting means being so related to the circumference of the rollers that the peripheral speed of each roller is greater than that of the roller directly above, the rollers mounted in the movable bearings being independently rotatable, resilient means for urging the movable bearings towards the stationary bearings, means comprising adjustable wedges to limit the movement of the bearings in a direction to decrease the distance between the roller surfaces, 30 said wedges resting on the upper surfaces of the channels, between the corresponding bearings, means for moving each wedge, comprising a bolt threadedly connected with the wedge and rotatable in openings in the flanges, and means 35 on the bolt for engaging a flange surface for resisting longitudinal movement of the bolt in the flange openings whereby when it is rotated it will move the wedge transversely of the channel.

2. In an ore pulverizing device having a plurality of pairs of superpositioned rollers, arranged for successively receiving and comminuting ore fed to the top pair of rollers, having a frame provided with a plurality of vertically spaced pairs of horizontal bearing supports, the supports of each pair being at the same height and horizontally spaced, two bearings on each support, one bearing on each support being stationary thereon and the other movable therealong, a power driven roller mounted between the stationary bearings on each pair of supports and another roller mounted between the corresponding movable bearings, the power driven rollers being the same size, the upper power driven roller having a pulley attached to one end for attachment to a power mechanism, means for interconnecting the several driven rollers to effect simultaneous rotation in the same direction, the gear ratios being so selected that the lower of any two vertically spaced rollers will turn at a greater peripheral speed than the one above, and means for limiting the distance between adjacent surfaces of rollers of each pair, comprising wedges positioned on the bearing supports, and means comprising a bolt threadedly connected with each wedge and rotatably connected with the support, for moving the wedge in the direction of the axes of the roller to effect a spacing of the bearings. 55

3. An ore pulverizing device having a frame, comprising a pair of parallel supports of channel shaped cross section, arranged with their flanges extending upwardly, two bearing blocks in the channel of each support, one of which is held against movement thereon, the other being movable along the support, the bearing blocks on each 70 75

support having aligned openings, a guide bar extending through the openings, and immovably attached to the stationary bearing block, a roller mounted for rotation between each pair of stationary bearing blocks, another roller rotatably mounted between each pair of movable bearing blocks, a wedge member positioned in each channel, one edge of the member being in engagement with one bearing block, the inclined side facing 5 the other bearing block, a complementary wedge member positioned between the inclined side of the first wedge member and the other bearing block, the complementary wedge member being shorter than the distance between the flanges

and provided with a threaded opening extending across the channel, the flanges of the channel having openings in axial alignment with the opening in the wedge member, and a threaded bolt 10 engaging the threaded openings and extending fully through the openings in the flanges, the bolt having heads engaging the outside of the flanges which prevent it from moving transversely of the channel, whereby when it is rotated it will move the wedge complementary members to effect an adjustment of the distance between the bearings and the rollers carried thereby. 10

CYRUS R. BROWN.
